United States Patent Office

Des. 192,987
Patented June 5, 1962

192,987

ENEMA BAG OR SIMILAR ARTICLE

Leonard F. Waldman, Jr., Niles, Ill.
(6301 Lincoln Ave., Morton Grove, Ill.)

Filed Oct. 10, 1961, Ser. No. 67,035

Term of patent 14 years

(Cl. D83—1)

The side not shown is substantially the same in appearance as the side shown.

I claim:

The ornamental design for an enema bag or similar article, substantially as shown and described.
